UNITED STATES PATENT OFFICE.

GEORGE W. SHIELDS, OF FLUSHING, NEW YORK.

SHIPPING AND STORAGE VESSEL.

1,175,906.

Specification of Letters Patent. Patented Mar. 14, 1916.

Application filed February 24, 1914. Serial No. 820,535.

To all whom it may concern:

Be it known that I, GEORGE W. SHIELDS, a citizen of the United States, residing at Flushing, Queens county, in the State of New York, have invented certain new and useful Improvements in Shipping and Storage Vessels, of which the following is a full, clear, and exact specification.

My invention relates to improvements in storing and shipping vessels and the same has for its object more particularly to provide a simple, efficient and reliable metal vessel which may be used either with or without an outer inclosing casing or shell made of wood or any other suitable or desirable material.

Further my invention has for its object to provide a metal vessel composed of a plurality of parts or sections having their edges conformed to each other and said conformed edges firmly secured together by an annular member or members.

Further said invention has for its object to provide a metal vessel composed of a plurality of sections having their adjoining edges folded together, to form a head or rim, and the edges of said head or rim firmly clamped or secured within an annular locking member disposed within said head or rim and which it serves to stiffen or reinforce.

To the attainment of the aforesaid objects and ends my invention consists in the novel details of construction, and in the combination, connection and arrangement of parts hereinafter more fully described and then pointed out in the claims.

In the accompanying drawings wherein like numerals of reference indicate like parts, Figure 1 is a central vertical section showing one form of vessel constructed according to and embodying my said invention; Fig. 2 is an enlarged detail vertical section showing the means for securing the adjoining edges of the barrel sections together, and the construction of the outer casing to receive said securing means; Fig. 3 is a central vertical section showing a cylindrical metal vessel composed of three parts or sections, and Fig. 4 is an enlarged detail section showing, in full lines, the transverse section showing, in full lines, the securing means preparatory to engaging the registering edges of the barrel sections, and, in broken lines, adjusted and engaging said edges.

In said drawings, referring to Figs. 1

and 2, 10 designates a container comprising an inner vessel 11 formed of sheet metal. The said inner vessel is shown as composed of two correspondingly shaped sections or parts 12, 13, of sheet metal pressed to form. Said sections or parts are provided at their contacting edges with laterally projecting flanges 12^a, 13^a, which are brought together and have their edges 12^b, 13^b, turned upwardly and thence inwardly and disposed within a transversely curved annular groove provided in an annular securing ring or member 15. The securing ring or member 15 is substantially square in transverse section and fits snugly within and serves to reinforce the outwardly and upwardly extending flanges of the vessel sections. The upper portion of the securing member 15 is rounded so that its outer edge 15^a may be easily turned down and caused to engage firmly with the inturned edges of the flange portions 12^b, 13^b, when pressure is applied to the upper surface of said securing member 15. 16 denotes an outer protecting casing or shell which in the present instance is shown in the form of a wooden barrel provided upon its inner surface with an annular recess or groove 17 which is adapted to receive the folded edges of the inner vessel together with the securing means therefor.

In the modification illustrated at Fig. 3 I have shown a metal vessel of cylindrical form comprising an intermediate section 20, and end sections 21, 22. The intermediate section 20 is provided at its opposite edges with outwardly projecting flanges 20^a, 20^b which are conformed to similar flanges 21^a, 22^a provided along the edges of the end sections 21, 22 respectively. The flanges are then secured together and to annular securing members 23, 24, respectively, in the same manner as in the main construction first above described.

It will be noted that my invention while applicable to vessels designed or intended for use without an inclosing casing or shell, are nevertheless applicable for use as an inner vessel or lining to be used in connection with an outer casing or shell of any kind or type.

Having thus described my invention, what I claim and desire to secure by Letters Patent is,—

1. A metal vessel comprising a plurality of sections having conforming adjoining

edges, coincidently folded angular flanges extending outwardly from said adjoining edges, and an annular, substantially rectangular securing member having two opposite 5 site and one intermediate side in contact with, and embraced by said angular flanges and the side of said vessel, and having an annular groove adjacent to one of its remaining intermediate sides adapted to receive and hold the registering edges of said flanges, substantially as specified.

2. A metal vessel comprising a plurality of sections having conforming adjoining edges, coincidently folded angular flanges 10 extending outwardly from said adjoining edges, and an annular substantially rectangular securing member having two opposite sides and one intermediate side in contact with and embraced by said angular flanges and the side of said vessel, and having a horizontal, transversely curved annular groove 15 therein adjacent to the other of its intermediate sides adapted to receive and hold the registering inwardly-turned edges of said flanges, and an outer receptacle inclosing said metal vessel and provided with an annular recess to receive the folded, flanged edges of said metal vessel and the securing means therefor, substantially as specified.

20 3. A metal vessel comprising a plurality of sections having conforming adjoining edges, coincidently folded angular flanges and the side of said vessel, and having a horizontal, transversely curved annular groove 25 therein adjacent to the other of its intermediate sides adapted to receive and hold the registering inwardly-turned edges of said flanges, substantially as specified.

of sections having conforming adjoining edges, coincidently folded angular flanges extending outwardly from said adjoining edges, an annular substantially rectangular securing member having two opposite sides and one intermediate side in contact with and embraced by said angular flanges and the side of said vessel, and having a horizontal, transversely curved annular groove 30 35 therein adjacent to the other of its intermediate sides adapted to receive and hold the registering inwardly-turned edges of said flanges, and an outer receptacle inclosing said metal vessel and provided with an annular recess to receive the folded, flanged edges of said metal vessel and the securing means therefor, substantially as specified.

Signed at the city of New York, in the county of New York, and State of New York, this 2d day of February, one thousand nine hundred and fourteen.

GEORGE W. SHIELDS.
